UNITED STATES PATENT OFFICE.

WALTER U. FORSCHLER, OF NORWICH, CONNECTICUT.

ELECTRICAL FIXTURE.

Application filed April 8, 1922. Serial No. 550,856.

To all whom it may concern:

Be it known that I, WALTER U. FORSCHLER, a citizen of the United States, residing at Norwich, in the county of New London and 5 State of Connecticut, have invented certain new and useful Improvements in Electrical Fixtures, of which the following is a specification.

This invention relates to electrical fixtures 10 and the primary object of the invention is to provide novel means for connecting a receptacle and a light fixture to a single outlet box, so that electrical appliances, such as sad irons, curling irons and the like can be 15 conveniently attached in place without the necessity of providing a base board or wall receptacle.

The use of electrical appliances requires 20 their attachment to wall receptacles, base board receptacles or to light fixture sockets. Owing to the additional cost of providing base board or wall receptacles, ordinary houses are provided only at a few advantageous places with the said base board 25 or wall receptacles. When the electric appliances are connected to light sockets, the use of the light is precluded unless a double socket is provided, and the attachment of appliances to an ordinary light socket presents a clumsy and unsightly appearance. 30

It is therefore another prime object of the invention to provide a neat and attractive member for connection with an ordinary outlet box embodying novel means for supporting any type of electric light fixture and 35 a receptacle for the plug of an electric appliance, the member being rotatably connected with the outlet box so that the receptacle can be moved to various positions in relation 40 to the box.

A further object of the invention is the provision of an insulator ring for connection with the outlet box, the ring having means for receiving various sizes of canopies of a light fixture, and a receptacle for 45 receiving the plug of an electric appliance, the receptacle being connected with the wires extending into the outlet box.

A further object of the invention is to provide 50 a novel means for connecting the insulator ring with the box, so that the ring can be swung about the box without change in the box structure and without disturbing the

light fixture supported by the box and insulator ring. 51

A still further object of the invention is to provide an improved electric fixture of the above character, which will be durable and efficient in use, one that will be simple and easy to manufacture, and one which can be placed upon the market at a reasonable cost. 60

With these and other objects in view, the invention consists in the novel construction, arrangement and formation of parts, as will be hereinafter more specifically described, claimed and illustrated in the accompanying drawings, forming a part of this specification, in which drawings:

Figure 1 is a front elevation of the improved combined electric fixture. 70

Figure 2 is a central longitudinal section through the same, taken on the line 2—2 of Figure 1.

Figure 3 is a vertical longitudinal section 75 through the improved combined electric fixture showing the same connected with an outlet box and having an electric light fixture and electric appliance plug provided therewith, the outlet box being shown in section. 80

Figure 4 is a detail rear elevation of the socket portion of the receptacle of the improved electric fixture.

Figure 5 is a detail transverse section 85 through the receptacle portion of the improved fixture taken on the line 5—5 of Figure 1.

Figure 6 is a fragmentary sectional view 90 through the lower portion of the fixture, showing the ways therethrough provided for the feed wires for the electric appliance receptacle.

Figure 7 is a detail plan view of the blank for one of the contacts of the receptacle.

Figure 8 is a detail elevation of one of the 95 contacts of the receptacle.

Figure 9 is a section through the same taken on the line 9—9 of Figure 8.

Referring to the drawings in detail, wherein similar reference characters designate corresponding parts throughout the several views, the letter A generally indicates the improved electric fixture; B, an outlet box with which it is associated; C an electric light fixture; and D a plug for association with the electric appliance. 100 105

The improved fixture A is adapted to be placed flush up against a wall or other support E and in abutting engagement with the outer face of the outlet box B as clearly shown in Figure 3 of the drawings.

The outlet box B is of the usual or any preferred construction, and includes the ordinary cast iron body 10 provided with the inwardly extending apertured ears 11 for receiving the usual fastening screws of a light fixture or the face plate of a switch box. The central portion of the body 10 also supports the usual U-shaped bracket 12 having the outwardly extending feet 13 for receiving the bolts 14 for holding a light fixture C in position. The body 10 of course, supports the usual conduits 15 for the electric feed wires 16.

The lighting fixture C may be of the ordinary or any preferred character and includes the ordinary canopy 17 having the annular base flange 18. The plug D for the electric appliance which is to be connected with the receptacle forming a part of the fixture A can be of any preferred type, and as shown includes the knife contacts 19 carried by the body 20. The electric cord for the electric appliance as indicated by the numeral 21 is of course, connected in the ordinary manner with the knife contacts 19.

The improved electric fixture A is preferably formed of insulation, such as porcelain, fiber or the like, and includes the annular body 22, the inner periphery of which is rabbeted as at 23 to provide an annular shoulder 24, the purpose of which will be hereinafter more fully described. The outer face of the annular body 22 is provided with a plurality of concentrically disposed annular grooves 25, in which is adapted to fit the base flange 18 of the canopy 17 forming a part of the electric fixture C. It can be seen that by providing a plurality of the annular grooves 25, canopies of different sizes can be readily associated with the improved fixture. The walls of the grooves serve as convenient means for supporting the canopy of the fixture.

The body 22 at one point is provided with radially extending head 30, which forms a part of the outlet receptacle. This head 30 is provided with a circular recess 31, for the reception of the body portion 32 of the outlet receptacle. The body portion 32 of the outlet receptacle is formed separate from the head 30, so as to facilitate the connection of the electric wires 33 therewith, which are extended through ways 34 formed in the annular body 22 and the head 30 provided for that purpose. These ways 34, of course, communicate with the circular recess 31. The inner wall of the recess 31 is provided with integral lugs 35 disposed at diametrically opposite points, and these lugs are provided with openings 36 for the reception of retain-

ing bolts 37, utilized for holding the body 32 of the receptacle in position in the recess. The body 32 of the receptacle has its inner face notched as at 38 for receiving the lugs 35 and the body is provided with ways 39 which are adapted to align with the openings or ways 36 for the reception of the bolts 37. The body 32 of the receptacle is provided with diametrically aligned T-shaped ways 40, which are adapted to receive contact blades 19 of a plug 20. These ways 40 are formed T-shaped so that if the blades of a plug are diametrically aligned or if they are disposed in spaced parallel relation, they can be associated with the body 32. The contacts 41 of the receptacle are disposed within the T-shaped openings 40, and are riveted or otherwise secured to face plates 42, which can be secured to the inner surface of the body 32 by fastening elements, such as screws 43. The contacts 41 are of a novel construction and are preferably formed of a single blank of metal as shown in Figure 7 of the drawings. This blank as shown includes the T-shaped body 45, having the arms 46, 47 and 48 which are adapted to be bent at right angles to a base portion 49 of the blank. The outer terminals of the arms 46, 47 and 48 can be bent back upon themselves to form resilient tongues 49 for frictionally engaging the knife contacts 19 of a plug 20. It is obvious that the arms 46, 47 and 48 owing to their peculiar arrangement will frictionally engage the knife contacts 19 of a plug irrespective of whether these contacts are arranged in diametric alignment or whether they are disposed in spaced parallel relation.

In order to retain the fixture A in position in relation to the outlet box B, a retaining ring 50 is provided. This ring 50 can be formed of metal if so desired, and is adapted to fit upon the shoulder 24 formed by the rabbeted portion 23. This ring is provided at diametrically opposite points with inwardly extending apertured ears 51 which are adapted to align with the ears 11 formed on the walls of the body 10 of the outlet box B and the aligned ears 51 and 11 are adapted to receive retaining bolts 52 as clearly shown in Figures 1 and 2 of the drawings. The ring 50 and the bolts 52 constitute an efficient means for holding the fixture A in position, and it can be seen that the fixture A can be rotated in relation to the box B and electric light fixture C without disturbing either one of the same when it is desired to position the heads 30 at different points around the box B. As shown the head 30 is disposed in the lower portion of the box.

When the outlet receptacle is not in use, an ornamental cap can be associated therewith if so desired, in order to impart a pleasing and attractive appearance to the fixture.

It can be seen that when it is desired to attach an electric appliance in position, it

is merely necessary to place the plug thereof and force the knife contacts into the openings 40 provided for that purpose.

From the foregoing description, it can be seen that an improved electric fixture has been provided which will effectively permit an electric light fixture and outlet receptacle to be attached to the single outlet box.

Changes in details may be made without departing from the spirit or scope of this invention; but,

I claim:

1. The combination with an outlet box and electric light fixture, of a support for the fixture including a body formed of insulation arranged to overlie the outlet box and an outlet receptacle comprising a body arranged to overlie the body, means formed in the body for supporting the electric light fixture, and a head formed on the body having contacts associated therewith for engaging with the contacts of a plug and electric appliance.

2. The combination with an outlet box, an electric light fixture, and a plug of an electric appliance, of a fixture including an annular body of insulation arranged to overlie the outlet box, means for securing the body to the outlet box, means formed on the body for receiving the electric light fixture, means for securing the fixture to the box, a head carried by the body, ways formed in the body and head for receiving the electric light wires from the outlet box, and contacts associated with the head and connected with the electric wires for frictionally engaging the contacts of the plug of the electric appliance when the plug is associated with said head.

40 3. The combination with an outlet box including a supporting bracket and attaching ears, an electric light fixture, and a plug of an electric appliance, of a fixture associated with the plug and lighting fixture including an annular body of insulation having a rabbeted portion forming a shoulder, a supporting ring arranged to engage the shoulder having ears arranged to align with the attaching ears of the outlet box, retaining bolts extended through the ears, the ring permitting rotation of the annular body, means formed on the outer surface of the body for receiving an electric light fixture, a head formed on the body, an outlet receptacle engaged with said head, contacts associated with said outlet receptacle, the body and head having ways extended there-

through for receiving the feed wires from the outlet box, the contacts being adapted to engage the contacts of the plug when the 60 plug is associated with the outlet receptacle.

4. The combination with an outlet box, an electric light fixture including a canopy, having an annular base flange, and a plug of an electric appliance, of an electric fixture including an annular body of insulation arranged to surround the outlet box, means for rotatably securing the annular body to the outlet box, the outer face of the annular body having grooves formed therein for the 70 reception of the base flange of the canopy of the electric light fixture, and a head formed on the annular body for the reception of the plug of the electric appliance.

5. As a new article of manufacture, an 75 electric light fixture comprising an annular body of insulation having concentric grooves formed in the outer face thereof, the inner periphery of the body being rabbeted to provide a shoulder, a radially extending head 80 formed on the body having a recess therein, an outlet receptacle having contacts therein and openings for the reception of contacts of a plug of an electric appliance, the head and body having ways formed therein for 85 the reception of electric feed wires.

6. As a new article of manufacture, an electric fixture including a body of insulation having an opening therethrough, the outer face of the body having grooves 90 formed therein, a radially extending head formed on the body having a recess therein, the inner wall of the recess provided with attaching lugs, a body fitted in the recess having notches arranged to receive the lugs, 95 clamping elements extending through the body and lugs, the body having T-shaped openings therethrough, and contacts arranged in said openings, the first and second mentioned bodies having ways for 100 electric wires formed therein.

7. As a new article of manufacture, an electric fixture including an annular body of insulation for supporting electric light fixtures, a head formed on the body of insulation for the reception of a plug and electric light fixture, the head having recesses therein of a T-shape, contacts disposed in said recesses including a plurality of contact arms arranged at right angles to each 105 other, and inwardly extending resilient tongues formed on the outer ends of said arms.

WALTER U. FORSCHLER.
